APPLICATOR DISPENSERS HAVING ROTATABLE DISCS

Ralph H. Thomas, Clark, N.J., assignor to Bristol-Myers Company, New York, N.Y., a corporation of Delaware

Filed Mar. 6, 1961, Ser. No. 93,448
5 Claims. (Cl. 15—571)

The present invention pertains to fluid dispensing containers and applicators and more particularly to a container for dispensing and applying liquids by means of a plurality of rotatable discs.

Liquid dispensers comprising ball-top containers are well known to the prior art but have the disadvantage that the rate at which liquid may be dispensed from such devices is relatively low by reason of the fact that the contact between the rotatable ball and the surface to which the liquid is to be applied is substantially only a line contact.

Prior art dispensers utilizing a rotatable cylinder are also known but it has been commonly found to be difficult or impossible to effect tight seals between such rotatable cylindrical applying means and the support means therefor. Consequently, such prior art devices have been utilized primarily for the dispensing of relatively viscous materials such as shaving cream and the like.

Therefore it is an object of the present invention to provide a dispenser having a series of rotatable applicators which will afford a large area of dispensing contact.

It is another object of the invention to provide a dispenser applicator which can be effectively sealed to prevent escape of even the most mobile fluids from the dispenser.

A further object of the invention is to provide a dispenser applicator having a reserve supply of fluid associated with the applicator for instant use when needed.

In accordance with the foregoing objects, the invention comprises a container having a fluid reservoir and a flanged open end. A resilient applicator supporting and retaining means comprising a hollow, sleeve-like member is provided having an open, inner, circular extremity for removable attachment to the flange of the container. The other outer extremity of the member has a closed diaphragm provided with a plurality of serially arranged slots. A rotatable applicator assembly comprising a shaft having a number of discs concentrically mounted thereon is inserted within the closure member with an upper minor portion of the discs extending through and beyond the slots. The diameter of the discs is greater than the length of the slots. Means are provided for supporting the shaft and discs within the closure. The ends of the slots are slightly spaced from at least a portion of the peripheries of the corresponding discs to define fluid dispensing spaces. Opposed walls of the resilient closure member are provided externally at their lower portion with cammable surfaces. A cap relatively rigid as compared to the resilient applicator supporting and retaining member is adapted for removable attachment to the container adjacent the open end thereof. The cap is provided internally with camming surfaces for engagement with the cammable surfaces of the resilient closure member whereby, when the cap is secured to the container, the opposed end walls of the resilient member are inwardly deformed below the shaft supporting means whereby the shaft and the associated discs are forced outwardly of the container into a tight sealing engagement with the slots to prevent escape of fluid from the container.

The invention will now be described in more detail with reference to the appended drawings in which identical numerals refer to identical parts and wherein:

FIG. 1 is a perspective view of the applying end of a

2

partially disassembled fluid dispenser and a partially cut away cooperating cap constructed in accordance with this invention;

FIG. 2 is a cross-sectional elevation of the applying end of the assembled dispenser applicator and cap illustrated in FIG. 1;

FIG. 3 is a top plan view of a modified applicator dispenser having the cap removed and the discs omitted for clarity;

10 FIG. 4 is an enlarged fragmentary view of the modification shown in FIG. 3; and

FIG. 5 is a fragmentary, sectional elevational of a modified disc construction.

Referring now to the drawings, and particularly to 15 FIGS. 1 and 2. The dispenser comprises a container 16 forming a liquid reservoir. The container 16 is provided with an open end 17 having an outwardly directed annular flange 18 extending about the periphery thereof. The container is provided, adjacent the upper end thereof, 20 with exterior screw threads 19.

A closure member is provided having an open, lower, ring-like portion 22 provided internally thereof with an annular groove 23 for engagement with the flange 18. The closure member is also provided with an upper substantially elliptical portion comprising an applicator supporting and retaining means designated generally by the numeral 24 which is closed by a web or diaphragm 26 provided with a plurality of serially arranged, rectangular apertures or slots 27 which are more fully illustrated in 30 FIG. 3. Two opposed walls 28 of the applicator supporting means 24 are curvilinear in form and are provided internally adjacent but slightly spaced from the diaphragm 26 with bearing portions comprising mutually aligned depressions or sockets 29 for the support and retention 35 thereof at the extremities of a shaft 31. Mounted upon and spaced from the extremities of the shaft 31 and from each other are a plurality of flat discs 32 having an upper minor portion thereof extending through the slots 27 and projecting therebeyond. The sockets 29 may be so positioned with respect to the diaphragm 26 and the discs 32 40 may be so dimensioned that in the assembled operating position of the dispenser, the discs are spaced a slight distance from the end walls 15 of the slots 27 to define fluid dispensing spaces. (Shown in FIG. 1.)

The closure member is formed of a suitable material 45 such as rubber, polyethylene or the like which is relatively resiliently deformable compared to the material from which the container 16 is constructed. In use inversion of the dispenser covers the shaft 31 and the portions of the discs 32 within the closure member with fluid which 50 may then be transferred by the flat edges of the discs, to the exterior of the container and applied to a surface by rolling the discs over the surface. Obviously the dimensions of the spaces which are provided between the peripheries of the discs and the ends of the slots in the unsealed position should be determined in accordance with the physical properties of the liquid to be dispensed and the rate at which it is desired to dispense the fluid. The 55 sides of the discs in each of the illustrated embodiments of this invention are in frictional contact with the slots 27 to prevent escape of fluid in both the sealed and unsealed 60 positions.

Sealing of the dispenser of FIGS. 1 and 2 during non-use thereof is accomplished by providing the opposed walls 28 of supporting means 24 with external cammable 65 surfaces which may take the form of vertical ridges 34. A cap designated generally by the numeral 35 of material relatively rigid compared to the resilient material of the closure member, comprises a skirt 40 provided, near the open end, with interior threads 36 for engagement with the threads 19 on the container 16. The interior 70 of the cap is further provided with a camming surface

comprising a reduced diameter portion 30 connected with the skirt 40 by a bevel 37 engageable with the cammable surfaces or ridges 34 on the closure member whereby when the cap is tightened onto the container 16, the lower portions of the walls 28 are deformed inwardly of the closure member and parallel to the longitudinal axis of shaft 31 whereby the latter, with associated discs 32, is forced outwardly of the container into tight sealing engagement with the ends 15 of the slots 27 to prevent escape of fluid from dispensing spaces of the container. Upon detachment of the cap from the container the inwardly directed force upon the ridges 34 is removed and the walls 28 resume their normal, unbiased position to allow the discs 32 to drop away from the ends of the slots under the force of gravity.

The upper edges of the slots 27 may also be provided, as shown in FIG. 4, with inwardly projecting lips 44 which are in constant contact with the sides of the discs whereby escape of fluid from the container past the sides of the discs is prevented.

An additional feature of the invention is the provision of a secondary reservoir of fluid for immediate dispensing which consists of the spaces between the discs where fluids may be held by capillary attraction.

Alternatively as illustrated in FIG. 5, the edges of the discs 53 may be serrated and the discs dimensioned so that the crowns of the serrations contact the ends of the slots whereby fluid is prevented from escaping from the container except for that held by capillary attraction within the spaces between the serrations. The serrated disc can be employed with any of the various embodiments for supporting and journaling the shaft.

Fluid dispensers constructed in accordance with the foregoing embodiments are especially useful in their ability to dispense and to apply to surfaces relatively large amounts of fluid and are also desirable because of the large quantity of fluid held in reserve on the large surface area of the discs and accessible for instant application. Moreover, such fluid dispensers are conveniently useable for applying fluids to the hair since the rotatable discs act somewhat in the nature of the teeth of a comb.

The fluid dispensing applicators constructed in accordance with the invention may be made in any desired size and may be used to dispense materials of a wide variety such as fluid cosmetics, medicinals, inks, adhesives, etc.

The applicator of the various embodiments here described may be constructed of any suitable material but is preferably of a moldable plastic material such as polyethylene which is, in itself, resiliently deformable, hence aids in the establishment of tight seals between the applicator and the walls of the aperture of the closure member.

It is to be understood that the foregoing description is merely illustrative of the principles of the invention and that modifications within the capacity of one skilled in the art are to be included within the scope of the invention.

This application is a continuation-in-part of my co-pending application, Serial No. 756,772, filed August 25, 1958, now abandoned.

What is claimed is:

1. A fluid dispensing applicator comprising a container having an open end, a hollow, resiliently deformable closure member attached about said open end, said closure member having inner opposed bearing means outwardly of said container open end at right angles to the longer axis of the slots, a plurality of flat discs rotatably mounted within said closure means, the diameter of said discs being greater than the length of the said longer axis of the slots,

said discs extending through said slots and projecting therebeyond said discs having flat applying edge surfaces normally spaced from the end walls of said slots to permit fluid from the container to be dispensed thereby, means to prevent escape of fluid between the side walls of the discs and the slots, said discs being mounted on an elongated shaft journaled within said bearing means and adapted for limited movement normally with respect to the diaphragm, cammable surfaces on opposed walls of said closure member between the container open end and the opposed bearing means actuatable to inwardly deform those portions of said opposed walls in a direction parallel to the axis of the shaft, a rigid cap for attachment to said container about said closure member, and camming surfaces on the interior of said cap which, when said cap is attached to said container, actuate said cammable surfaces whereby the said shaft and discs are moved normally with respect to said diaphragm to close the fluid dispensing spaces.

2. A fluid dispensing applicator of claim 1 wherein the applying edge surfaces of said discs have a series of transverse radial serrations.

3. The fluid dispensing applicator of claim 1 wherein the discs are rotatably mounted on said shaft.

4. The fluid dispensing applicator of claim 1 wherein the discs are non-rotatably mounted on said shaft.

5. A fluid dispensing applicator comprising a container having an open end, a hollow, resiliently deformable closure member attached about said open end, said closure provided with a diaphragm having a plurality of serially arranged elongated slots outwardly of said container open end and in spaced relationship thereto, said closure member having inner opposed bearing means outwardly of said container open end at right angles to the longer axis of the slots, a plurality of discs rotatably mounted within said closure means, the diameter of said discs being greater than the length of the longer axis of said slots, said discs extending through said slots and projecting therebeyond, said discs having applying edge surfaces normally spaced from the walls of said slots to permit fluid from the container to be dispensed thereby, said slots having the outline of a chordal cross-section through said discs, said discs being mounted on an elongated shaft journaled within said bearing means and adapted for limited movement normally with respect to the diaphragm, cammable surfaces on opposed walls of said closure member between the container open end and the opposed bearing means actuatable to inwardly deform those portions of said opposed walls in a direction parallel to the axis of the shaft, a rigid cap for attachment to said container about said closure member, and camming surfaces on the interior of said cap which, when said cap is attached to said container, actuate said cammable surfaces whereby the said shaft and discs are moved normally with respect to said diaphragm to close the fluid dispensing spaces.
